UNITED STATES PATENT OFFICE.

WENZL RICHARD FISCHER, OF BELLEVUE, PENNSYLVANIA.

RAIL-JOINT.

1,107,923.

Specification of Letters Patent. Patented Aug. 18, 1914.

Application filed September 19, 1913. Serial No. 790,765.

To all whom it may concern:

Be it known that I, WENZL RICHARD FISCHER, a citizen of the United States of America, residing at Bellevue, in the county 5 of Allegheny and State of Pennsylvania, have invented certain new and useful Improvements in Rail-Joints, of which the following is a specification, reference being had therein to the accompanying drawings.

10 This invention relates to rail joints, and has for its object to provide a rail joint, in a manner as hereinafter set forth, whereby the opposing ends of a pair of rails are connected together without the employment of 15 nuts and bolts, at the same time providing for the necessary contraction and expansion of the track rails when connected together.

Further objects of the invention are to provide a rail joint which is simple in its 20 construction and arrangement, strong, durable, efficient in its use, conveniently set up and inexpensive.

With the foregoing and other objects in view, the invention consists of the novel construction, combination and arrangement of parts to be hereinafter more specifically described and illustrated in the accompanying drawings wherein is shown an embodiment 25 of the invention, but it is to be understood, that changes, variations and modifications 30 can be resorted to which come within the scope of the claim hereto appended.

In the drawings wherein like reference characters denote corresponding parts 35 throughout the several views:—Figure 1 is a side elevation of a rail joint in accordance with this invention, Fig. 2 is a top plan partly in section, Fig. 3 is a section on line X—X Fig. 2, and Fig. 4 is a section on line 40 Y—Y Fig. 2.

Referring to the drawings in detail, 5 and 6 denote a pair of track rails with one end of the rail 5 opposing the end of the rail 6. The web 7 of each of said rails is provided 45 with a rectangular opening 8 and the web 7 of each of said rails, at each end is cut away as at 9. When the rails 5 and 6 are arranged in longitudinal alinement, the cut

away portion of one rail opposes the cut away portion 9 of the other rail thereby providing a rectangular opening. 50

The reference character 10 denotes an inner fish plate which is arranged against one side of the webs of the rails 5 and 6 and further overlaps the bases 11 of the said 55 rails, the inner fish plate being flanged as at 12. The inner face of the fish plate 10 has projecting laterally therefrom a series of tongues 13, which extend through and project from the openings 8 as well as extending 60 through and projecting from the opening formed by the cut away portions 9.

The reference character 14 denotes an outer fish plate which is formed with a series of openings 15 for the passage of the tongues 65 13. Each of the tongues 13 is formed, near its outer end with a rectangular opening 16, having the outer side wall 17 thereof beveled and extending through the opening 16 of the tongues 13, is a longitudinally extending 70 wedge 18 for coupling the inner and outer fish plates together and for further coupling the said fish plates with the rails whereby the tongues 13 will prevent longitudinal shifting of the track rails 5 and 6. 75 For securing the wedge 18 in position, a cotter pin 19 extends therethrough and is adapted to abut against one of the tongues 13 as clearly shown in Fig. 2.

What I claim is:—

80
In a rail joint, the combination with a pair of rails, comprising base, web and tread portions, having their ends opposing each other and with the web at the opposing ends cut away, said cut away portions registering 85 to provide an opening, an inner fish plate positioned against one side of said rails and having its face portion bent over to over-lap the base of the rails and having its upper portion formed with integral lateral tongues 90 extending through and projecting from said opening, each of said tongues being formed adjacent to the outer ends with a rectangular opening, the outer walls each being beveled, an outer fish plate formed with an 95 opening adapted for the reception of said

tongue and adapted for engagement with the outer sides of said rails and having its base portion bent over to over-lap the face of said rails, and a wedge extending through the openings of said tongues and engaging the outer fish plate for connecting the said fish plates together, and a pin extending through the wedge and abutting against the

outer fish plate for retaining the wedge in position.

In testimony whereof I affix my signature in the presence of two witnesses.

WENZL RICHARD FISCHER.
